LLP; Klaus P. Stoffel

(57) **CLAIM**

The ornamental design for a vehicle taillight as shown and described.

DESCRIPTION

FIG. 1 is a front view of a first embodiment a vehicle taillight showing the present design;

FIG. 2 is a front and left side perspective view thereof;

FIG. 3 is a front, top and left side perspective view thereof;

FIG. 4 is a left side view thereof;

FIG. 5 is a front view of a second embodiment of a vehicle taillight showing the present design, the second embodiment being a mirror image of the first embodiment;

FIG. 6 is a front and right side perspective view thereof, being a mirror image of FIG. 2;

FIG. 7 is a front, top and right side perspective view thereof, being a mirror image of FIG. 3; and,

FIG. 8 is a right side view thereof, being a mirror image of FIG. 4.

The features shown in broken lines form no part of the claimed design.

1 Claim, 8 Drawing Sheets
